UNITED STATES PATENT OFFICE.

NICOLA M. GUILLOW, OF WAKEFIELD, ASSIGNOR OF ONE-HALF TO JEHIEL D. GUILLOW, OF BOSTON, MASSACHUSETTS.

ROD-HOLDING CLAMP FOR CHILDREN'S CARRIAGES.

SPECIFICATION forming part of Letters Patent No. 351,322, dated October 19, 1886.

Application filed July 26, 1886. Serial No. 209,088. (No model.)

To all whom it may concern:

Be it known that I, NICOLA M. GUILLOW, of Wakefield, in the county of Middlesex and State of Massachusetts, have invented certain new and useful Improvements in Rod-Holding Clamps for Children's Carriages, of which the following is a description, reference being had to the accompanying drawings, in which—

Figure 1 is a side view of a carriage having my improved device attached thereto. Fig. 2 is a side view in detail of said device, one-half of the bracket being removed to show the remaining parts. Fig. 3 is a plan view thereof, the same being in section in the plane of the line *a*, Fig. 2, viewed in the direction of the arrow there shown. Fig. 4 is a rear view of said device, and Fig. 5 is a detail view of the clamping-block.

Like letters of reference indicate like parts in the different figures.

The object of my invention is to provide an adjustable support for holding the rod from which the canopy is suspended in children's carriages, which object I accomplish in the manner hereinafter more particularly described and claimed.

A in the drawings represents the body of a child's carriage, to which is rigidly attached, by means of screws or in any well-known way, a bracket, B, which serves as a support for and forms a part of said adjustable clamp. Said bracket is preferably provided with four supporting-legs, *b*, which are joined together in one piece, the interior of which is hollow or concave in form, as shown at *b'*, Figs. 2 and 3. Through the portion of said bracket in which the legs converge I provide a hole for the reception of a screw-threaded rod, C, which is provided with a hand-nut, *c*, and preferably with a safety-nut, *c'*, secured tightly thereon to prevent said hand-nut from being lost.

The inner end of the rod C is provided with a longitudinal slot, into which is loosely inserted a block, D, (better shown in Figs. 2 and 5,) said block being provided with an oblong slot, *d*, Figs. 3 and 5, through which is inserted a pin, *d'*, which holds said block normally in place, while the latter is permitted to move lengthwise of the slot in the part C. An elongated stirrup or clasp, E, is also loosely secured to the part C by means of the pin *d'*,

as clearly shown in Figs. 2 and 3. The rod F, from which the canopy is suspended, is inserted between the clasp E and block D. The height and position of said rod is then adjusted, when it is clamped in place by means of the hand-nut *e*. Upon loosening said hand-nut it is obvious that the rod F may be raised or lowered, while the canopy may be thrown back or forward or adjusted laterally with reference to the carriage-body, as may be found necessary, the semicircular portion of the block conforming as it does to the hollow *b'*, and permitting a forward or backward adjustment, while the part C has a swivel movement in the bracket. As the block D rests against the interior of the bracket, the slot *d* permits the part C to be drawn back, and with it the clasp E, which presses the rod F firmly against the block D. Thus it is obvious that by means of my improved device the rod F may be adjusted to any position desired and firmly retained in the manner set forth.

To prevent the rod F from dropping down when the screw *e* is loosened, the clasp E may be extended upward, as indicated in dotted lines in Fig. 2, and caused to surround the rod F, to which it may be secured by a secondary thumb-nut, as represented. It is obvious that said construction would possess certain practical advantages without varying the essential features of my invention.

I am familiar with the construction shown in Patent No. 344,883 to C. W. Trow, and I make no claim to the features described therein.

What I do claim, and desire to secure by Letters Patent, is—

1. In an adjustable rod-holding clamp for children's carriages, the combination of the bracket B, screw C, connected by a knuckle-joint to the part E, slotted block D, and nut *c*, substantially as and for the purposes set forth.

2. In a rod-holding clamp for children's carriages, the slotted semicircular block D and means for clamping the same against the rod, substantially as and for the purposes specified.

NICOLA M. GUILLOW.
